UNITED STATES PATENT OFFICE.

OSCAR J. LEINS, OF MILWAUKEE, WISCONSIN, ASSIGNOR TO MILWAUKEE GAS SPECIALTY COMPANY, A CORPORATION OF WISCONSIN.

SEPARATOR MECHANISM.

Application filed March 30, 1925. Serial No. 19,258.

My invention relates to separating mechanism for the separation of the balls, slugs, pebs, or other burnishing objects from the parts which were burnished thereby. My invention may be incorporated in a separate machine for receiving the entire mixture from a burnishing machine and for separating the burnished parts, or the invention may be incorporated in an attachment for burnishing machines to be applied to such machines to be driven therewith to receive and to separate the burnishing and burnished parts, after a burnishing operation has been completed.

In the practice heretofore, the contents of a burnishing machine barrel are dumped, after a burnishing operation, into a riddle which is then actuated to effect discharge of the balls, slugs, or other burnishing objects. This has been a very laborious procedure as the burnishing balls will fill any depressions or pockets in the burnished objects and these objects must, in greater parts, be turned over by hand to discharge the burnishing members. It is therefore an important object of my invention to provide a mechanism from which the burnishing balls or other members can be quickly ridled from the mixture and the work automatically agitated to clear itself of all burnishing members, and to provide such mechanism with means for automatically discharging the burnishing members into one receptacle and the finished burnished objects into another receptacle.

My improved mechanism is clearly shown on the accompanying drawings, in which

Fig. 1 is a plan view of the end of a burnishing machine barrel with my separator attachment thereon;

Fig. 2 is an enlarged sectional view on plane 2-2, Figure 1;

Fig. 3 is an end elevational view of the attachment;

Fig. 4 is a sectional view on plane 4-4, Figure 2;

Fig. 5 is a sectional view on plane 5-5, Figure 2;

Fig. 6 is a sectional view on plane 6-6, Figure 2; and

Fig. 7 is a sectional view on plane 7-7, Figure 6.

On the drawings, 10 represents the barrel or drum of a well known type of burnishing machine, such barrel having the flange

11 at its end on which are pivoted the lock bolts 12. It is understood that in this type of machine, the barrel is supported in a yoke frame to be axially rotated or to be swung to vertical position when being filled with a charge preparatory to a burnishing operation. The separating attachment shown comprises an annular base structure 13 which has the seating flange 14 for engaging the flange 11 of the burnishing machine barrel to be rigidly secured thereto by means of the latch bolts 12 and with its passageway 15 in register with the barrel interior. Before the attachment is applied to the barrel, the barrel cover or closure plate (not shown), is held to the barrel by the bolts 12. When the attachment is to be applied the cover is removed and the attachment substituted.

A cylindrical riddle frame or drum 16 formed of suitable perforated metal or screen, receives and surrounds the annular base 13 and is held in place by the surrounding band 17 and the screws 18, the riddle frame being thus coaxial with the barrel 10 and in communication therewith through the passageway 15.

After my improved attachment has been applied to a burnishing machine barrel after a burnishing operation, the barrel is inclined with the attachment end foremost, and the barrel with the attachment thereon is then revolved so that the entire contents of the barrel will travel into the riddle frame from which the burnishing balls or other members or particles escape, the burnished work traveling toward the outer end of the riddle frame to be eventually delivered therefrom. In order to hold the burnished objects in the riddle drum until the burnishing balls have been entirely removed therefrom and discharged from the riddle frame, and also to control the discharge of burnished objects from the riddle drum for both left handed or right handed rotation, I have provided a special outlet controlling structure in the ends of the riddle drum. Secured at the outer end of the riddle drum is the closure and reenforcing frame 19, which has the flange 20 receiving the riddle frame and to which it is secured by screws 21 and a ring or hoop 22. The frame or wall 19 has the central passageway or outlet opening 23 which is shown as being rectangular. Depending

inwardly from opposed sides in said opening are the triangular walls 24 and 25, between which the discharge plate or shutter 26 is operable. This plate has trunnion pins 27 and 28 extending from the opposite edges thereof and journaled in the apexes of the walls 24 and 25. Each wall has a longitudinal pocket 29 for receiving a latch member 30 secured to the respective trunnion pin. Above the pocket in each wall is a spring pressed latch plunger 31. These plungers cooperate with the eccentric projections 31' or the latch members 30 to yieldingly lock the discharge plate 26 against either of the opposite edges E or E' of the opening 23.

Surrounding the outlet opening 23 and extending inwardly from the wall 19 is a scoop frame having the opposite scoop ends 32 and 33. The scoop frame is secured against the wall 19 by its flanges 34, the inner walls 35 and 36 of the scoop sections being separated by a space or passageway 37 in which the inner end of the discharge plate 26 swings to engage either against the wall 35 or the wall 36. The scoop frame engages against the triangular wall 25, as shown in Fig. 5, so that each scoop end together with the discharge plate 26 will form a scoop or discharge passageway to the outlet 23. When the discharge plate 26 is in the position shown in Figure 2, and the attachment is driven in counterclockwise direction (from the left of Fig. 2), the burnished objects will be taken up at the periphery of the drum 16 and transmitted through the scoop part 33 to the discharge plate 26 and from them out through the discharge outlet 23. When the attachment rotates in a clockwise direction, the scoop section 32 will gather up the burnished objects and will transmit them to the discharge plate 26 and through the outlet 23, the plate 26 having been swung over into engagement with the edge E' and with the edge of the wall section 36. Any objects gathering in the scoop sections behind the discharge plate 26 will fall back into the drum through the space 37.

In order to entirely close the outlet 23 so that the objects can be retained in the riddle drum until all the burnishing balls have been separated, I provide a door or cover plate 39 for the discharge outlet 23. This cover plate may be hinged to the outer end of the discharge plate 26 to be swung in either direction to close the discharge outlet 23. When it is desired to discharge from the riddle drum, the cover plate 39 is swung away from the discharge outlet and locked in the dotted line position shown in Figure 2. In order that this discharge plate 26 may be readily set for left or right hand discharge, the trunnion shaft 28 has the extension 40 provided with a handle 41.

In order to facilitate the collection of the burnishing balls or other material as they fall through the riddle drum opening, I surround the riddle drum by a casing which receives the burnishing material and from which it may be readily discharged into a receptacle. A flange or conical frame 42 is secured to the base 13 by means of screws 43 and from this frame or flange extends sheet metal frame work comprising the inner section 44 and the conical section 45. The section 44 is secured at the inner end through the frame 42 and the outer end of the section 45 is secured to the end frame 19 of the riddle drum. The frame 42 has the L-shape extension 46 surrounding the part 44 and at its inner end, the part 45 has the flange 47 secured to the outer edge of the extension 46 so that an annular trough 48 will be formed around the part 44. In this part 44 there is a discharge gap or opening 49 (Fig. 4), and diametrically opposite this opening the wall 46 has the discharge outlet 50 from the trough 48. As the separator attachment is rotated, the burnishing balls or material fall from the riddle drum into the collector casing and travel down through the passage 49 into the trough 48 from which they are discharged into a suitable receptacle from the outlet 50.

The separator attachment can be of light construction so that it can be readily handled by one man. The attachment effects considerable saving in time and labor as it requires just a short time to secure it in place on the burnishing machine barrel whereafter separation, riddling and discharge of the burnishing material and burnished work will be accomplished entirely automatically. Changes in modifications can, of course, be made which will still come within the scope of the invention, and I do not, therefore, desire to be limited to precisely what I have shown and described.

I claim as follows:

1. In a separator structure, the combination of a perforated drum having an inlet at one end for mixed large and small objects to be separated, there being a discharge outlet at the other end of said drum of less width than said drum, a scoop structure for scooping up the larger objects when the drum rotates in one direction, another scoop structure for scooping up the larger objects when the drum rotates in the opposite direction, a discharge plate adjustable to connect either one of said scoops with said discharge outlet, and means for rotating said drum, the smaller objects falling through the drum perforations.

2. A separator structure comprising a riddle drum, a supporting base for the drum adapted for supporting the inlet end of said drum to receive a mixture to be

separated, a discharge outlet at the other end of said drum displaced from the drum periphery, a discharge scoop for transmitting the larger objects from the drum per-

5 6. In a separator structure, the combination of a perforated drum having an inlet at one end for objects to be separated and having a discharge outlet in the other end of less width than said drum, a crescent shaped scoop structure adjacent to said discharge outlet and having an opening in its inner side opposite said discharge outlet, each side of said scoop structure forming a scoop inlet, and a discharge plate pivoted immediate said discharge outlet and said 60

10 at one side with said casing discharge outlet and having an outlet at its opposite side.

3. In a separator structure, the combination of a perforated drum having an inlet at one end for large and small objects to be separated, there being a discharge outlet in the other end of said drum of less width than said drum, a scoop structure adjacent to said discharge outlet having a scoop inlet at each side and having an opening in its inner wall 15 opposite to the discharge outlet, a discharge plate within said scoop structure between said discharge outlet and opening, said discharge plate in one position opening one of the scoop inlets to said discharge outlet and 20 closing the other scoop inlet, said other scoop inlet being then in communication with the interior of the drum through said opening.

4. In a separator structure, the combination of a perforated drum having an inlet at one end for large and small objects to be separated, there being a discharge outlet in the other end of said drum of less width than said drum, a scoop structure adjacent to said discharge outlet and having a scoop inlet 25 at each end and an opening in its inner wall, a discharge plate pivoted intermediate said discharge outlet and said opening, said discharge plate in one position opening one end of said scoop structure to the discharge outlet and closing it to the interior drum, and 30 closing the other scoop inlet to the discharge outlet and opening it to the drum through said opening.

5. In a separator structure, the combination of a perforated drum having an inlet at one end, and a discharge outlet in its other end of less width than said drum, parallel walls extending from said outer end at the sides of said discharge outlet, a discharge 35 plate pivoted between said walls, a scoop structure surrounding said walls and discharge plate and having a scoop inlet at each side, said discharge plate and walls forming a discharge chute, said discharge plate when 40 swung to one position connecting said discharge chute with one scoop side of said scoop structure and closing the other side of the scoop structure to the discharge outlet.

6. In a separator structure, the combination of a perforated drum having an inlet at one end for objects to be separated and having a discharge outlet in the other end of less width than said drum, a crescent shaped scoop structure adjacent to said discharge outlet and having an opening in its inner side opposite said discharge outlet, each side of said scoop structure forming a scoop inlet, and a discharge plate pivoted immediate said discharge outlet and said 65

70 opening and adapted to extend diagonally through said discharge outlet and opening and across said scoop structure, said discharge plate when in one position opening one side of said scoop structure to said discharge outlet and when in another position opening the other side of said scoop structure to the discharge outlet, each scoop side when closed to the discharge outlet being in communication with the interior of said 75 drum through said opening.

7. In a separator structure, the combination of a perforated cylindrical drum having an inlet at one end for large and small objects to be separated, and having a discharge outlet in its other end of less width than said drum, scoop mechanism at said discharge outlet for raising the larger objects from said drum and discharging them through said discharge outlet, the smaller 80 particles falling through said drum perforations, an imperforate frusto-conical shell surrounding said drum and having its base adjacent to the said drum inlet, an annular trough surrounding the base of said shell, a 85 communicating passageway between said trough and the shell interior through which the smaller particles pass to the trough, and a discharge outlet for said trough diametrically opposite the said communicating passageway.

8. In a separator structure, the combination of a perforated drum having an inlet at one end for mixed large and small objects to be separated and having a discharge outlet at the other end for the large objects, said discharge outlet being of less diameter than said drum, a scoop structure adjacent to said outlet having an inlet for receiving objects when the drum rotates in one direction 105 and having another inlet for receiving objects when the drum rotates in the opposite direction, and means for selectively connecting either scoop inlet with said discharge outlet.

In witness whereof, I hereunto subscribe my name this 27 day of March, 1925.

OSCAR J. LEINS.
